UNITED STATES PATENT OFFICE.

BURT KING BUNCH, OF MARSHALL, MISSOURI.

ELECTRIC LANTERN.

1,130,567.

Specification of Letters Patent. Patented Mar. 2, 1915.

Application filed August 5, 1914. Serial No. 855,158.

To all whom it may concern:

Be it known that I, BURT KING BUNCH, a citizen of the United States, residing at Marshall, in the county of Saline and State 5 of Missouri, have invented certain new and useful Improvements in Electric Lanterns; and I do hereby declare the following to be a full, clear, and exact description of the invention, such as will enable others skilled in 10 the art to which it appertains to make and use the same.

This invention comprehends certain new and useful improvements in electric lanterns and has for its primary object to provide 15 a device of this character which will be of extremely simple construction as well as highly efficient in use.

Another object of this invention is to provide an electric lantern of this character 20 including a combined hood and handle support formed of a single blank of material and bent for engagement upon a dry battery to convert the same into an electric lantern.

The invention has for another object to 25 provide a device of this character which will be extremely cheap to manufacture and will include novel contact members caused by the swinging handle and the dry battery for completing the circuit through the electric 30 bulb back of the bull's-eye lens and supported in the reflector when the handle is in operative or raised position.

The invention has for a further object to 35 generally improve and simplify the construction and operation of devices of this character and increase the efficiency thereof without increasing the cost of the same.

With these and other objects in view as 40 will become more apparent as the description proceeds, the invention consists in certain novel feature of construction, combination and arrangement of parts as will be hereinafter more fully described and claimed.

45 For a complete understanding of my invention, reference is to be had to the following description and accompanying drawings, in which—

Figure 1 is a front elevation of the complete device, Fig. 2 is a side elevation thereof, Fig. 3 is a top plan view, Fig. 4 is a vertical transverse section with the handle in raised position and the battery shown in elevation, Fig. 5 is a longitudinal vertical 55 section through parts of the device to be

mounted upon the dry battery, and Fig. 6 is a plan view of the hood in blank form.

Referring in detail to the drawings by numerals, 1 designates a dry battery which has a central binding post 2 and a forward binding post 3 mounted in the top thereof and with which my invention is connected to convert the dry battery 1 into an electric lantern, as will be later clearly apparent.

Mounted upon the binding post 2 is a flat 65 contact plate 4 which has its outer end 5 offset upwardly for engagement by the swinging contact plate 6 mounted upon the inwardly projecting end 7 of the swinging handle 8 which has mounted centrally thereon the hand-grip 9 formed of insulating material. The contact plate 6 is swung into engagement with the upwardly offset free end 5 of the contact plate 4 when the swinging handle 8 is swung to its operative or 70 upper position for the purpose of carrying the lantern from place to place. The opposite ends of the handle 8 are pivotally mounted in the upper perforated end of the 75 opposite upstanding ears 10 formed on the 80 battery encircling arms 11 of the hood 12, said arms 11 projecting rearwardly from the hood 12 and being connected at their free ends at the rear side of the battery 1 by solder or other suitable means; one of 85 said arms having formed in its rear or free end an upstanding ear 13 having a perforation 14 in its upper extremity above the top of the battery 1 to permit the entire device 90 to be suspended upon a nail or other suitable suspending member.

The hood 12 projects forwardly from the upper portion of the battery 1 and has its upper end snugly engaged with the latter and is provided with a rearwardly directed 95 perforated ear 15 which is engaged over the binding post 3 and is suitably insulated from the upper rear end of the spring connecting plate 16 which is also engaged over the binding post 3 beneath the ear 15, the lower forward end of the connecting plate 16 being secured to the electric bulb 17 which is mounted centrally in the concavo-convex reflector plate 18 which is secured in the outer end of the hood 12 and retained in place 100 by its snug engagement with said hood 12. A bull's-eye lens 19 or the like is also engaged in the outer end of the hood 12 outwardly of the reflector plate 18. It will be understood that the reflector plate 18 is 110

preferably formed of metal and serves as an electrical connection between the bulb 17 and the hood 12, while the connecting plate 16 forms an electrical connection between 5 the bulb 17 and the binding post 3, whereby a circuit will be completed through the bulb 17 when the handle 8 is in its operative or upper position, the current flowing through the handle 8, to the ears 10, along 10 the arms 11 to the body of the hood 12 and to the bulb 17 by means of the reflector plate 18 and back from the bulb 17 to the binding post 3 by way of the connecting plate 16, as will be readily understood. It will also 15 be evident that when the handle 8 is swung to its inoperative or lower position, the circuit will be broken. By referring to Fig. 6, it will also be readily seen that the hood 12 is divided along its lower portion and the 20 opposite ends of the body of the blank from which the hood and arms 11 with the ears 10 and 13 are formed, may be connected by solder or any other suitable means. It will also be apparent that the complete device 25 may be readily and cheaply manufactured and will be highly efficient in use.

While I have shown and described the preferred embodiment of my invention, it will be understood that minor changes in 30 the details of construction, combination and arrangement of parts may be made without departing from the spirit and scope of the invention as claimed or sacrificing any of the advantages thereof.

35 What is claimed is:—

1. A device of the class described comprising the combination with a battery; of a hood secured upon said battery, a handle supported by said hood, a contact plate carried by said battery, a bulb mounted in said hood, means for forming electrical connections between said battery and said bulb, and a contact plate carried by said handle for engagement with the first mentioned 40 contact plate to complete a circuit through said bulb.

2. A device of the class described comprising the combination with a battery; of a contact plate carried by said battery, a 45 hood mounted upon said battery, a lens se-

cured in said hood, a reflector plate secured in said hood, a bulb mounted in said reflector plate, said reflector plate having connections with said hood, electrical connections between said bulb and said battery, 55 handle supporting members projecting upwardly from said hood, a handle mounted in said handle supporting members, and a contact plate carried by said handle for engagement with the first mentioned contact plate upon movement of said handle to operative position.

3. A device of the class described comprising the combination with a battery; of a hood formed of a single blank bent into 60 circular form and having opposite arms for engagement around the battery, said arms projecting from one end of the hood, and being connected at their rear ends to secure said hood upon said battery, upstanding ears formed on said arms, one of said upstanding ears being provided with an opening to receive a suspending member by means of which the device may be suspended upon a stationary support, a handle mounted in the remaining ears, said battery having a pair of binding posts, a contact plate projecting from one of said binding posts, a combined reflector and bulb support mounted in said hood, a lens for the offset 70 combined reflector and bulb support, a bulb mounted in said combined reflector and bulb support, a connecting plate extending from said bulb to the section binding post of the battery, an ear projecting from said hood 75 and engaged upon the last mentioned binding post and insulated from the same and from the connecting plate, and a contact plate carried by the handle for engagement with the first mentioned contact plate to 80 complete a circuit through said battery and bulb upon movement of the handle to operative position.

In testimony whereof I affix my signature in presence of two witnesses.

BURT KING BUNCH.
